CLAIM

The ornamental design for a thumb piano, as shown and described.

DESCRIPTION

FIG. 1 is a front, right and bottom perspective view of a thumb piano showing my new design;
FIG. 2 is a rear, left and top perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged partial view of FIG. 1; and,
FIG. 10 is an enlarged partial view of FIG. 5.
The broken lines in the figures illustrate portions of the thumb piano that form no part of the claimed design.
